(57) **CLAIM**

The ornamental design for an infusion pump for pharmaceutical drugs, as shown and described.

DESCRIPTION

FIG. 1 is a perspective view of an infusion pump for pharmaceutical drugs showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a bottom perspective thereof.
